United States Patent Office.

R. M. McGRATH, OF LAFAYETTE, INDIANA.

Letters Patent No. 73,738, dated January 28, 1868.

IMPROVEMENT IN THIMBLE-SKEINS.

The Schedule referred to in these Letters Patent and making part of the same.

TO ALL WHOM IT MAY CONCERN:

Be it known that I, R. M. McGRATH, of Lafayette, in the State of Indiana, have invented a certain new and useful Improvement on Thimble-Skeins; and I do hereby declare that the following is a full, clear, and exact description of the same, reference being had to the accompanying drawings, and to the letters and marks thereon, which said drawings form part of this specification and show my invention as applied to the ordinary thimble-skein.

The cast-iron thimble-skein is very liable to fracture and breakage at the ends, the loss to dealers and wagon-makers in some instances reaching as high as twenty per cent. on their stock on account of such breakage. In order to obviate this loss, and to render the thimble-skein durable, I connect or add to the ends liable to fracture wrought-iron bands or supports.

The thimble-skein *a*, shown by the drawings, has around its larger and inner end a wrought-iron band, *b*, and within its outer or smaller end a like band or support, *c*. The thimble-skein is shown as being within the box *d*, and the view that of a longitudinal section. The band *b* on the larger end will more commonly be "shrunk on," and that, *c*, at the smaller end will generally be placed in the flask or mould and united to the end by the casting, though both may be fitted on, or in either way, by "shrinking" or by casting. The width or size of the bands or supports may be greater or less than here shown, the intention being to give to the ends full and ample support to protect the cast metal from injury by handling, and to increase the durability of the thimble-skein.

What I claim as my invention, and desire to secure by Letters Patent, is—

As a new article of manufacture, the thimble-skein, of cast iron, with wrought-iron bands or supports, as herein set forth.

This specification signed this 26th day of November, 1867.

R. M. McGRATH.
